UNITED STATES PATENT OFFICE

LAWRENCE KINNAIRD, OF BERKELEY, CALIFORNIA

EDUCATIONAL TESTING DEVICE

Application filed July 12, 1929. Serial No. 377,863.

This invention relates to an educational testing device.

The principal object of this invention is to provide means whereby a pupil may answer any number of questions after which the examination card may be quickly examined to determine the grade to be received by the student.

Another object is to produce a device of this character which is equally applicable to geographical questions as well as to other types of questions.

A further object is to provide means whereby a stub may be retained by the school upon which stub will appear the student's name, the date of the examination and any other directions concerning the examination, as well as the grade the student received.

Other objects and advantages will be apparent during the course of the following description.

In the accompanying drawings forming a part of this specification, and in which like numerals are employed to designate like parts throughout the same,

Figure I discloses a student's examination card,

Figure II discloses the teacher's examination grade card,

Figure III is an enlarged detail fragmentary view showing the manner in which the two cards are used, and

Figure IV is a plan view of a sticker for use in correcting an error.

It is common practice in giving examinations to give a series of questions and a series of possible answers for these questions. The problem is for the student to select the proper answer to fit the question. It is a difficult matter to correct this type of examination and consequently it requires many hours of tedious work on the part of the teacher to grade the student.

I have therefore devised examination cards having certain indicia thereon and certain characteristics to be later described which will immediately indicate whether the question has been properly answered or not.

In the accompanying drawings wherein

preferred embodiment of my invention, the numeral 5 designates the student's card upon which is imprinted a plurality of horizontal lines 6 and vertical lines 7. These horizontal lines and vertical lines form boxes 8 in which circles 9 are printed. In the vertical columns are placed numerals to indicate the number of the answer while in the column 11 is placed the question number. Also imprinted on the surface of the card may be maps as shown in detail at 12. Above this matter are certain indicia to indicate the course, the student's name, the date of the examination and other special directions for the examination.

A space 13 is provided adjacent to one of the margins of the card and adjacent to the perforated line 14. This perforated line forms the outer portion of the card into a stub 16 also having a space 17 for the grade marking. This stub also carries indicia indicating the course, name, date of examination and other directions.

The teacher's card indicated as a whole by the numeral 18 is identical with the student's card with the exception that a portion 19 is printed a characteristic color, the reason for which will be later seen.

In using my cards, the student is given a list of questions and possible answers and a punch. It is then necessary for the student to select the proper answer, and assuming that question 1 is asked, the proper answer is answer 5 and he will therefore punch out the card material in the first horizontal column under the numeral 5 in the vertical column.

Supposing however that he selects the wrong answer, as for instance, answer 3 and punches out the card material in the vertical column 3. The teacher, in preparing the master card, will punch with her punch the material in the horizontal column and vertical column 5, then in grading the student's card, when the teacher's card is placed behind the student's card the colored surface of the teacher's card will show through in the column 3 indicating a wrong answer. Had the student punched the correct answer the punch in his card would overlie the punch

in the teacher's card and therefore no color would show there-through.

It will therefore be apparent that the teacher can very quickly ascertain the number of wrong answers and deduct this number from the total it is possible to make in the examination.

When employing the cards for locating points upon the map, the same system is em-

- 10 ployed with the exception that the student points out that area of the map which he feels is correct for the question given. As soon as the teacher has determined the grade the student is to receive, the grade is marked in
- 15 the spaces 13 and 17, the stub 16 torn from the student card and filed for future reference. The student card is returned to the student, or a reverse procedure is followed, that is the student card may be retained and
- 20 the stub given to the student. This is a matter of selection on the part of the teacher.

It is to be understood that the form of my invention herewith shown and described is to be taken as a preferred example of the same, and that various changes relative to the shape, size, material and arrangement of parts may be resorted to without departing from the spirit of the invention, or the scope of the subjoined claims.

- 25 30 Having thus described my invention, I claim:-

1. In an educational device, two cards having similar indicia adapted to be in vertical registry when said cards are superposed, certain of said indicia being in sets, one set defining horizontal columns, another set defining vertical columns, said sets crossing each other to define spaces, one set of columns having indicia to indicate respective questions, the other set having indicia to designate respective ones of said other columns to indicate spaces for respective answer indications where said columns cross each other, whereby one or more of several possible answers to respective questions may be indicated by punching in one or more of said spaces, one of said cards being punched to indicate correct answers and becoming thereby a master card, the other, constituting a test card and adapted to be punched to indicate answers, whereby when said master card is placed in registry over said test card any correct answer indications of said test card will register with the answer indications of said master card, and when said master card is placed behind said test card, the master card will show through and thereby render conspicuous any incorrect answer indication of the test card and any failure to indicate answers will be visible on the face of the test card.

2. In an educational device, two cards having similar indicia adapted to be in vertical registry when said cards are superposed, certain of said indicia being in sets, one set defining horizontal columns, another set de-

fining vertical columns, said sets crossing each other to define spaces, one set of columns having indicia to indicate respective questions, the other set having indicia to designate respective ones of said other columns to indicate spaces for respective answer indications where said columns cross each other, whereby one or more of several possible answers to respective questions may be indicated by punching in one or more of said spaces, one of said cards being punched to indicate correct answers and becoming thereby a master card, the other, constituting a test card and adapted to be punched to indicate answers, whereby when said master card is placed in registry over said test card any correct answer indications of said test card will register with the answer indications of said master card, and when said master card is placed behind said test card, the master card will show through and thereby render conspicuous any incorrect answer indication of the test card and any failure to indicate answers will be visible on the face of the test card, the cards differing from each other in color whereby the master card can be more readily seen through any incorrect indications in the test card.

In testimony whereof I affix my signature.

LAWRENCE KINNAIRD.
